UNITED STATES PATENT OFFICE.

JOHN M. VAN ORDEN, OF NEWARK, NEW JERSEY.

CORSET-COVER.

SPECIFICATION forming part of Letters Patent No. 705,725, dated July 29, 1902.

Application filed May 14, 1902. Serial No. 107,254. (No model.)

To all whom it may concern:

Be it known that I, JOHN M. VAN ORDEN, a citizen of the United States, and a resident of Newark, Essex county, New Jersey, have invented certain new and useful Improvements in Corset-Covers, of which the following is a specification.

This invention relates to a corset-cover which may be readily adjusted to the different measurements of waist and bust, so that the garment may be accurately fitted either loosely or closely, as may be desired. At the same time garments of one and the same size may be fitted to ladies having different figures, so that a multiplicity of sizes in the manufacture of the goods may be avoided.

In the accompanying drawings, Figure 1 is a front view of my improved corset-cover, showing it closed. Fig. 2 is a rear view thereof; Fig. 3, a front view showing it open, and Fig. 4 a rear view with the upper section slightly raised to expose the lower section.

The corset-cover is formed of two sections A and B. The upper and outer section A has armholes *a*, covers the back, sides, and shoulders, and runs out at the front in two forwardly-extending tapering flaps *a'*, adapted to be interknotted at the center of the bust. By tightening or slackening the knot the garment may be readily fitted to different bust measurements. Above each armhole *a* the shoulder-strap *a'* is divided and tied together by ribbon *c*, by means of which an adjustment to the length of waist and shoulder may be effected. The lower and inner section B forms a shield in front of the waist and runs out in two rearwardly-extending tapering flaps *b*, adapted to be tied together by ribbons *e* at the center of the back. The flaps *b* cover the waist, and their connected ends are concealed underneath the outer section A, Fig. 2. By tightening or slackening the connection *e* the garment may be fitted to different waist

measurements. The front shield of the lower section B is covered partly by the flaps *a'* of the upper section A and projects above and below the same. It is adjustably and removably connected thereto by ribbons *d*, which secure its upper corners to the upper edges of the flaps *a'*. This fastening permits a ready fitting of the garment to the size of the bust. If desired, one corner of the shield may be permanently connected to the upper section, while the other corner is adapted to be tied thereto.

In use the lower section B is first secured in position, and then the upper section A is drawn over it and connected thereto by the ribbons *d*, after which the flaps *a'* are interknotted. In this way a close fit may be obtained, and the garment may be readily adjusted to the different sizes of bust and waist measurement.

The garment may be either provided with seams or made seamless, as may be desired.

What I claim is—

1. A corset-cover composed of an upper section having forwardly-extending flaps that are adapted to be connected over the bust, and of a lower section having rearwardly-extending flaps that are adapted to be connected at the back, substantially as specified.

2. A corset-cover composed of an upper section having forwardly-extending flaps adapted to be interknotted over the bust, a lower section having rearwardly-extending flaps, means for adjustably connecting said rearwardly-extending flaps at the back, and means for connecting the upper section with the lower section, substantially as specified.

Signed by me at New York city, New York, this 13th day of May, 1902.

JOHN M. VAN ORDEN.
